UNITED STATES PATENT OFFICE.

FREDERICK G. HODELL, OF CLEVELAND, OHIO, ASSIGNOR TO THE CHAIN PRODUCTS COMPANY, OF CLEVELAND, OHIO, A CORPORATION OF OHIO.

CABINET.

Application filed March 12, 1927. Serial No. 174,832.

This invention relates to a manner of distributing merchandising and fabricating tire chains of a type known as "custom made" and more particularly to means for practicing the same, embracing a novel form of packaging comprising a chain batch and shipping container, and a combined stock containing cabinet, work bench and display sales device, adapted for use with the package.

The invention comprises generally improvements over that disclosed in the pending application of Howard Wilcox, Serial No. 92,775, filed March 6th, 1926, which in part discloses a method of making up chains to fit accurately the specific tires for which the chains are required, by selecting one of a relatively small number of sizes of long lengths of stock chain and cutting the desired relatively short length from this size.

That application discloses also a vending cabinet combining the features of display stand, stock container and work bench, provided with a number of bins corresponding with the number of stock chains of long stock chain lengths necessarily carried by the dealer. Such stock chain lengths are originally distributed in shipping containers of width to receive the stock chain in laterally extended position the length and height of the container being of dimension sufficient to receive the entire long stock length of chain folded back and forth upon itself.

My invention contemplates briefly, separating the stock chain lengths each in a batch laid as upon itself in superposed parallel layers, and providing for each batch a shipping container adapted to confine the chain length as arranged, shipping the chain in these containers and instead of transferring the long chain lengths from the barrel customarily employed as shipping container, into their respective bins in the vending cabinet, merely removing the tops of the shipping containers and thereafter sliding the same into the vending cabinet.

The exact nature of the invention will be apparent from the following description taken in connection with the accompanying drawings in which Fig. 1 is a rear elevation of a vending cabinet in which my invention has been incorporated and Fig. 2 is a typical section through the same.

According to my invention instead of

shipping the several long chain lengths indiscriminately together as in a barrel I prepare each chain length as a batch by laying the same in spread ladder form in superposed parallel layers; that is the chain length in spread form may be rolled upon itself, laid back and forth upon itself in chain folds, or similarly arranged so that the width of the batch is that of the spread ladder form chain and so that the chain may be continuously withdrawn from the batch without entanglement, beginning with the outer or top layer. For each batch so arranged I provide a shipping container of width to closely fit its size chain as laid, and of course, of other dimensions to receive the batch. The top of the container is arranged for convenient removal so that the chain may be progressively withdrawn upwards from the batch within it. The batch of chain and container therefor forms a package adapted for shipment; so that several packages of varying sizes corresponding to the desired stock size of chain will complete a dealer's stock of chain sizes.

The vending cabinet is formed preferably of sheet metal in any convenient manner and comprises the rectangular sides 1, bottom 2, and front wall 3 in outer dimension, the lower portion of the cabinet forming a compartment 4, well or bin adapted to receive the shipping containers 5, 5', 5'', etc., in which the several batches of corresponding various sizes of stock chain lengths are received by the dealer.

The upper portion of the cabinet may be provided along its front or display face with a number of bins 6 and similarly along its rear face with a number of bins 7, 7', 7'', etc., adapted to receive connecting links to be secured to the lengths of the chain cut from the long stock lengths in the compartment below. Above the bin 7', etc., is preferably a wooden table 8 which serves as a work bench. The bins 6 and 7 are spaced apart as indicated in Fig. 2 to form between them a well 11, leading from the respective shipping containers upwards to hooks 9 upon the rear surface of a display head 10 which is provided with suitable advertising matter upon its front surface, as may be also the front wall 3.

In practice as the chain packages are received by the dealer the tops of the shipping containers are removed and the con-

ainers slid into the compartment 4 in the lower portion of the cabinet; the upper end of the chain of each batch is thereafter brought upward through the well 11 and secured upon the proper hook 9 as indicated in the drawings. Thereafter the chain may be removed from its batch layer after layer upward through the well without entanglement and the dealer makes up from the stock 10 chain lengths, tire chains as required, in the usual and well known manner and all as explained in detail in the copending application referred to.

What I claim is:

- 15 1. In a tire chain display apparatus, a cabinet having a compartment open at its front end and provided with an opening in the top and having a display rack above said top opening, said compartment being adapted to receive a shipping container slid thereinto through its open end as a drawer and containing a batch of chain laid in superposed parallel layers and laterally confining said layers as laid, and said display rack being adapted to support an end of chain extending from said container in said compartment through said top opening.
- 20 2. In a tire chain display apparatus, a cabinet having a compartment open at its front end and provided with an opening laterally extending along its top, and a plurality of shipping containers in said compartment, each container having a batch of chain laid in superposed parallel layers and laterally confining the layers of its chain batch as laid and forming a drawer slideable in said compartment through the open end thereof to and from a position beneath said top opening thereof, said cabinet having a

display rack extending along above said top opening and adapted to support the ends of chains extending from said containers through said top opening.

3. In a tire chain display apparatus, a cabinet having a compartment open at its front end and a plurality of shipping containers in said compartment each container having a batch of chain laid in superposed parallel layers and laterally confining the layers of its chain batch as laid and forming a drawer slideable in said compartment through the open end thereof, said compartment having an opening in its top extending laterally above said containers and midway of the front and rear ends thereof, whereby chain may be withdrawn from said containers through said top opening without tangling or twisting, said cabinet having a display rack extending along above said top opening and adapted to support the ends of chains extending from said containers through said opening.

4. In a tire chain display apparatus, a cabinet having a compartment open at one end and provided with an opening in the top and having a display rack above said top opening, said compartment being adapted to receive a shipping container slid thereinto through its open end as a drawer and containing a batch of chain, and said display rack being adapted to support an end of chain extending from said container in said compartment through said top opening.

In testimony whereof I hereby affix my ⁷⁵ signature.

FREDERICK G. HODELL.
